60, 61 and 62 which are normally beyond cap 26 externally of barrel 20. In co-operation with annular recesses 60, 61 and 62, end cap 26 is provided with an exterior detent, as shown in FIG. 2, the detent including a round wire spring 64, one terminal of which is coiled around a retaining screw 66. Wire spring 64 extends across a substantial portion of end cap 26 and, as shown in FIGS. 2 and 3, is so located that the wire spring engages annular recesses 60, 61 and 62 as plunger holder 50 reciprocates back and forth through end cap 26.

10 The device of the present invention is so constructed that when plunger 48 and plunger holder 50 are urged under finger pressure through bore 22 of barrel 20 and capillary tube 40 against the tension of spring 24, and when the outer terminal of plunger holder 50 is uniplanar 15 with the outer planar surface of end cap 26, then the opposite terminal of plunger 48 protrudes approximately one-sixteenth of an inch beyond capillary tube 40. This insures complete delivery of the liquid sample from capillary tube 40, even when plunger holder 50 sinks slightly 20 into the flesh of the finger tip, preventing the terminal of the holder from lying coplanar with end cap 26.

As fluid is drawn into the capillary tube by permitting the tension of coil spring 24 to reverse the direction of movement of the plunger and plunger holder, then liquid 25 is drawn into tube 40. As spring detent 64 engages annular recess 60, the user of the device "feels" the contact of the spring and recess, and is immediately advised that a specified amount of liquid, e.g. one microliter, has been drawn into capillary tube 40. In like manner, the user is 30 also advised when the spring detent 64 engages recesses 61 and 62 that additional quantities of liquid have been drawn into the capillary tube, e.g. two microliters and three microliters.

It is also a salient part of the present invention to provide means for limiting the length of the stroke of plunger 48 and plunger holder 50. These inserts comprise cylindrical sleeves 68 and 70 which are adapted to be selectively placed within axial bore 22 of barrel 20.

As shown in FIG. 8, insert 68, for example, may be 40 inserted into bore 22 by first removing end cap 26 and then fitting the insert over the body of plunger holder 50. The insert is slid along the body of the plunger holder until the inner terminal thereof engages stop 56. End cap 26 is next threaded into bore 20, the extension portion 45 28 engaging the outermost terminal of the insert, thereby forcing the insert and plunger holder inwardly against the tension of spring 24.

As shown to advantage in FIG. 8, the length of the stroke of plunger holder 50 and plunger 48 is thereby 50 limited, so that upon full depression of the plunger holder, a lesser amount of liquid is drawn into the capillary tube 40 with the end cylindrical insert which is shown in FIG. 8, only one microliter of liquid is drawn into the capillary tube, and with the cylindrical insert shown in FIG. 7, two 55 microliters of liquid is drawn into the capillary tube. Various sizes of inserts may of course be employed to regulate the maximum amount of liquid which may be drawn into a capillary tube.

While the invention has been described, it will be 60 understood that it is capable of further modifications and this application is intended to cover any variations, uses, or adaptations of the invention following in general, the principles of the invention and including such departures from the present disclosure as come within known or customary practice in the art to which the invention pertains, and as may be applied to the essential features hereinbefore set forth and as fall within the scope of the invention or the limits of the appended claims.

What we claim is:

1. A microdispensing device comprising:

- (a) a barrel having a cap at one terminal thereof,
- (b) tube means inserted into the opposite terminal of said barrel,

- (c) a plunger movable through said barrel and said tube means for drawing liquid into and dispensing liquid from said tube means,
- (d) a plunger holder fixed to one terminal of said plunger,
- (e) said plunger holder extending through said cap and being provided with annular recesses,
- (f) detent means mounted on said cap for engagement with the annular recesses of said plunger holder,
- (g) whereby upon movement of said plunger, and plunger rod through said cap, said detent means selectively engages the annular recesses of said plunger holder in order that the user may "feel" when a predetermined amount of liquid has been drawn into, or dispensed from, said tube means,
- (h) spring means within said barrel for biasing said plunger holder outwardly of said barrel, and
- (i) an insert removably positioned within said barrel, for limiting the stroke of said plunger rod and thereby regulate the amount of liquid drawn into, and dispensed from, said tube means.

2. A microdispensing device comprising:

- (a) a barrel having a cap at the rear thereof,
- (b) a plunger extending through said barrel,
- (c) a plunger holder engaged with a terminal of said plunger, a portion of said plunger holder extending through said cap,
- (d) the opposite end of said barrel having a wall,
- (e) an axial bore extending through said barrel,
- (f) a segment of said wall being cut away from the outer periphery to the axial bore,
- (g) the axial bore in said wall rearwardly of the cut-away segment being of reduced diameter for the reception of said plunger,
- (h) tube means for insertion through the axial bore of the forward portion of said wall and through the cut-away portion of the barrel,
- (i) the inner terminal of said tube means abutting against that portion of the wall adjacent the cut-away segment, having an axial bore of reduced diameter,
- (j) whereby visual indication of the proper seating of said tube means in said barrel is afforded, and
- (k) means for holding said tube means in position within said barrel.

3. The microdispensing device of claim 2, wherein said means for holding said tube means in position within the barrel includes:

- (a) a collet threadedly engaged with the forward extremity of said barrel,
- (b) said collet being in retaining engagement with said tube means.

4. A microdispensing device including:

- (a) a barrel having an axial bore,
- (b) a cap covering one end of said barrel,
- (c) a wall at the opposite end of said barrel,
- (d) the forward portion of said wall being provided with a reduced axial bore of the forward portion of said wall,
- (e) a capillary tube inserted through the reduced axial bore of the forward portion of said wall,
- (f) a portion of said wall being cut away from the outer periphery of the wall to the axial bore thereof,
- (g) the remaining portion of said wall being further reduced in size to prevent the passage of said capillary tube therethrough,
- (h) whereby visual indication is afforded of the proper seating of said capillary tube,
- (i) a plunger extending axially through said barrel into said capillary tube,
- (j) plunger holder connected to the rear terminal of said plunger
- (k) said plunger holder extending through said cap, and

- (1) means for normally biasing said plunger and plunger holder in a rearward direction.
5. The microdispensing device of claim 4, wherein:
- the outer portion of said plunger holder is provided with a plurality of spaced annular recesses comprising graduations, and
  - a spring detent carried by said cap for engagement with the annular recesses of said plunger holder,
  - whereby the user can "feel" when a predetermined amount of liquid has been drawn into or expelled from, said capillary tube.

6. The microdispensing device of claim 5, with the addition of:

- inserts of different length selectively placed in said barrel between the terminal of said plunger holder and said cap, to limit the throw of said plunger and plunger holder, and the amount of liquid drawn into, and dispensed from, said capillary tube.

7. A microdispensing device comprising:

- a barrel having a cap at one terminal thereof,
- tube means inserted into the opposite terminal of said barrel,
- a plunger movable through said barrel and said tube means for drawing liquid into and dispensing liquid from said tube means,
- a plunger holder fixed to one terminal of said plunger,
- said plunger holder extending through said cap and being provided with annular recesses, and
- detent means mounted on said cap for engagement with the annular recesses of said plunger holder,
- whereby upon movement of said plunger, and plunger rod through said cap, said detent means selectively engages the annular recesses of said plunger holder in order that the user may "feel" when a predetermined amount of liquid has been drawn into, or dispensed from, said tube means,
- said barrel including a wall at the front end thereof,
- an axial bore in said wall,
- a portion of said wall being cut away from the outer periphery inwardly to the longitudinal axis of said wall,
- the axial bore in the forward portion of said wall being of a diameter to permit passage of said tube means therethrough,
- the size of the axial bore being reduced beyond the cut-away portion of the wall to permit passage of said plunger through the wall into said tube means while preventing rearward movement of said tube means beyond the cut-away portion of the wall,
- whereby visual indication is afforded of the proper location of said tube means.

8. The microdispensing device of claim 7, with the addition of:

- an extension protruding forwardly of said wall, and
- a collet threadedly engaged with said extension,
- said collet being in retaining engagement with said tube means.

9. A microdispensing device comprising:

- a barrel having a cap at one terminal thereof,

- tube means inserted into the opposite terminal of said barrel,
- a plunger movable through said barrel and said tube means for drawing liquid into and dispensing liquid from said tube means,
- a plunger holder fixed to one terminal of said plunger,
- said plunger holder extending through said cap and being provided with annular recesses, and
- an insert removably positioned within said barrel, for limiting the stroke of said plunger rod and thereby regulate the amount of liquid drawn into, and dispensed from, said tube means.

10. The microdispensing device of claim 9, with the addition of:

- inserts of different lengths selectively placed in said barrel between the terminal of said plunger holder and said cap, to limit the throw of said plunger and plunger holder, and the amount of liquid drawn into, and dispensed from, said capillary tube.

11. The microdispensing device of claim 9, wherein:

- said barrel includes a wall at the front end thereof,
- an axial bore in said wall,
- a portion of said wall being cut-away from the outer periphery inwardly to the longitudinal axis of said wall,
- the axial bore in the forward portion of said wall being of a diameter to permit passage of said tube means therethrough,
- the size of the axial bore being reduced beyond the cut-away portion of the wall to permit passage of said plunger through the wall into said tube means while preventing rearward movement of said tube means beyond the cut-away portion of the wall,
- whereby visual indication is afforded of the proper location of said tube means.

12. The microdispensing device of claim 11, with the addition of:

- an extension protruding forwardly of said wall, and
- a collet threadedly engaged with said extension,
- said collet being in retaining engagement with said tube means.
